UNITED STATES PATENT OFFICE.

G. RALSTON AYRES, OF PHILADELPHIA, PENNSYLVANIA.

DESIGN FOR A FABRIC FOR HORSE-BLANKETS.

SPECIFICATION forming part of Design No. 17,938, dated December 13, 1887.

Application filed April 6, 1887. Serial No. 233,938. Term of patent 14 years.

To all whom it may concern:

Be it known that I, G. RALSTON AYRES, a citizen of the United States, residing in Philadelphia, Pennsylvania, have invented a new and original Design for Horse-Blanket Fabrics, of which the following is a specification.

My design for a pattern for horse blanket fabrics is fully shown in the accompanying drawings, both of the figures of which embody the design.

The design consists of stripes *a* *a*, crossing each other at right angles to form a plaid, and each composed of bars *a'* on a suitable groundwork, the block *b*, inclosed by the plaid, being distinct in color or tint from the groundwork of the stripe. A second plaid is formed by other stripes, *d* *d*, each composed of bars *d'*, these stripes crossing each other in the blocks *b*.

As shown in Figure 1, the bars of the stripes

a are solid and those of the stripes *d* are composed of dashes, while in Fig. 2 the reverse is the case.

I claim—

The design for a pattern for horse-blanket fabrics, said design consisting of stripes *a*, forming a plaid inclosing blocks *b*, distinct from the groundwork of said inclosing plaid, and other stripes, *d*, forming a second plaid and crossing each other in the blocks *b*, all substantially as described and shown.

In testimony whereof I have signed my name to this specification in the presence of two subscribing witnesses.

G. RALSTON AYRES.
